UNITED STATES PATENT OFFICE.

ANDREW L. RIKER, OF FAIRFIELD, CONNECTICUT.

VENTILATOR.

Application filed April 13, 1923. Serial No. 631,785.

To all whom it may concern:

Be it known that ANDREW L. RIKER, a citizen of the United States, and resident of Fairfield, in the county of Fairfield and State of Connecticut, has invented certain new and useful Improvements in Ventilators, of which the following is a specification.

This invention relates to a ventilator, useful for many purposes, but more especially adapted for use as a closure for doors and the like.

An object of the invention is to provide a ventilator of simple construction which can serve as a closure for a door or the like to prevent a direct view through the ventilator from one side to the other of the door and to prevent the direct passage of air currents through the closure.

20 A further object is to provide a ventilator including spaced apart louvers capable of being incorporated in the opening of a door or the like to close the same without necessity of fitting the louvers to said opening.

25 A further object is to provide a ventilator which can be installed in openings of variable size in doors or the like without altering the elements of the ventilator or fitting them to the door, the construction of the 30 elements making the ventilating closure capable of being installed in an opening of greater or less size, within limits as will appear.

35 A still further object is to provide a novel and improved article of manufacture of the present character which can be furnished to the trade in two main units to be installed by unskilled workmen, the units being so constructed as to make it impossible to install the ventilator for use in any except the way it is intended to be installed.

Another object is to provide a ventilator consisting of two main units one of which can be arranged upon one side of an opening 45 and the other of which can be arranged upon the opposite side of said opening, and devices for securing the units to each other and against the surfaces of a door or the like adjacent the opening.

50 Another object is to provide a ventilator constituted by two units one of which consists of a louver and the other of which consists of a louver with simple slide, and devices adapted to connect the louvers with each other and to clamp the louvers against oppositely disposed surfaces adjacent an

opening in a door or the like without entering or in any way marring the surfaces of the door or the like.

Another object is to provide a ventilator 60 which can be secured in openings of doors or the like which vary in thickness, that is, in doors having their oppositely disposed surfaces adjacent their openings to be closed arranged at variable distances apart, without necessity for adjustment or alteration of the main units of the ventilator.

And yet another object is to provide a ventilator of the present character having a simple slotted or apertured slide associated 70 with a louver in novel and improved manner to be easily manipulated to allow openings through the ventilator or to close said openings.

With the above and other objects in view, 75 the invention comprises the construction, arrangement and combination of parts as now to be fully described and as hereinafter to be specifically claimed, it being understood that the disclosure herein is merely 80 illustrative of the principles of the invention and meant in no way in a limiting sense, changes in details of construction and arrangement of parts being permissible so long as within the scope of the appended 85 claims.

In the accompanying drawing forming a part of this specification,

Fig. 1 is an elevational view of a door or the like as seen from the inside of a building, showing the improved ventilator applied to use;

Fig. 2 is a sectional view on line 2—2 in Fig. 1, looking in the direction of the arrows;

Figs. 3 and 4 are perspective views of the outer and inner louvers of Figs. 1 and 2, showing the oblique flanges of said louvers extending in different direction from the plates or bodies of the louvers;

Fig. 5 is a perspective view of the slotted or apertured slide to be associated with one of the louvers of Figs. 3 and 4; and

Fig. 6 is an enlarged fragmentary sectional view on line 6—6 in Fig. 1.

With respect to the drawing and the characters and numerals of reference indicated thereon, A denotes a door or the like with opening B to receive a ventilating closure, and C and D denote, respectively, the outer and inner surfaces of said door adjacent the opening B. The ventilator of the present

invention is adapted to be clamped against the surfaces C and D to serve as a closure for said opening.

Numerals 10 and 11 denote louvers adapted to be clamped against the surfaces C and D, respectively, of the door A, each louver, naturally, being of the general configuration of the opening B, rectangular as shown.

Each louver may consist of a single piece of metal suitably shaped for its purpose, although either or both louvers could be constructed differently. That is to say, each louver 10, 11 consists of a desirably flat, rectangular plate or body 12 having a continuous, desirably L-shaped margin or double flange 13 comprising a continuous flange 14 adapted to lie in opening B when the ventilator is put to use and a continuous flange 15 adapted to engage a surface C or D as the case may be. The margin or double flange 13 need not be L-shaped, but each flange 14 should be of uniform width for its full length in order that the plates or bodies 12 of the louvers 10, 11 will be parallel with each other, and each flange 15 should be parallel with the plates or bodies 12 in order that the flanges 15 will lie snugly against the surfaces C, D, as will be understood. The continuous flanges 15 can be plain or can have any design intended to enhance the appearance of the ventilating closure.

Each plate or body 12 of the louvers 10, 11 is provided with slots or apertures 16 for the passage of air through the ventilator, and adjacent each slot or aperture 16 is a preferably obliquely disposed flange 17, all of the flanges 17 extending from the face of each plate or body 12 opposite the L-shaped margin or double flange 13. As disclosed, the flanges 17 extend nearly the width of the plates or bodies 12 and are constituted by metal struck from said plates or bodies to produce the slots or apertures 16.

In order that there can be no direct line of vision through the louvers when the elements of the ventilator are assembled, the slots or apertures 16 of the different louvers are arranged in staggered relation, and all of the oblique flanges 17 extend toward the same side of the ventilating closure, as best shown in Fig. 2 and Figs. 3 and 4, the flanges of Fig. 2 all extending toward the right of the ventilator and the flanges of Figs. 3 and 4 all being adapted to extend toward the left when the louvers are assembled to produce the closure.

Numeral 18 represents a slotted or apertured slide adapted to be suitably associated with one of the louvers. This slide may be associated with the inner louver 11 in the following manner: A lower strip 19, adjacent the bottom portion of the L-shaped margin 13, preferably extending about the length of the plate or body 12, may be drawn as at 20 to provide annular flanges

21 adapted to engage the face of said plate or body 12 to space the lower strip a sufficient distance from the plate or body 12 to allow insertion of the lower edge portion of the slide 18 between said plate or body and strip, and hollow rivets 22, passing through openings in the annular flanges and through openings 29 in the plate or body 12 of the louver 11, may be utilized to secure the lower strip 19 to said louver 11. See Figs. 2 and 6. After the slide is so inserted, an upper strip 19, adjacent the upper portion of the L-shaped margin 13 and extending approximately the length of the plate or body, may be secured to said plate or body in the exact manner of securing the lower strip to confine the upper edge portion of the slide. The slide is thus confined in the depression defined by the L-shaped margin and permanently associated with the louver 11, its sidewise movements, obviously, being limited by the annular flanges 21 or by the side portions of the L-shaped margin. As shown I utilize three sets of devices to hold each strip 19 to louver 11. Evidently, any number of strip retaining devices can be employed.

The slide 18 has apertures or slots 23 extending the greater part of the width thereof and arranged to correspond with the apertures or slots in the plate or body 12 of the louver 11. A manipulating handle 24, desirably arranged centrally of the slide, allows for ready adjustment of the slide to open or close the apertures or slots through the louver 11. The upper and lower edges of the slide may be cut away as at 25 (Fig. 5) in order that there will be no interference by the strip retaining devices when the slide is manipulated from one side toward the other of the ventilating closure.

The louver 10 may constitute a single unit of the ventilator, while the louver 11 with slide 18, strips 19, and hollow rivets 22 retaining the strips to louver 11, may constitute another unit, these being the two main units of the ventilating closure.

Numeral 26 denotes bushings, which may be carried by the louver 10, having threaded openings 27 to receive screws 28 adapted to pass through the hollow rivets 22 to hold the units of the ventilator to each other, it being understood that the arrangement of the bushings 26 upon the louver 10 corresponds with the arrangement of the hollow rivets in the louver 11.

The two main units constructed as illustrated and described can be furnished to the trade. It is apparent that any unskilled workman can install the units, placing one of the louvers so that its continuous flange 15 engages the surface C of the door A and the other unit so that its flange 15 engages the surface D, with the continuous flanges 14 and plates or bodies 12 lying adjacent each

other within the opening B. Evidently, no fitting of the units in the opening is required, the continuous flanges 14 being capable of being spaced a greater or less ⁵ distance from the wall of the opening B.

Several different arrangements could be employed for insuring that workmen cannot install the ventilator in any except the way it is intended to be installed. As shown, ¹⁰ one of the strip retaining devices including a hollow rivet to receive a louver clamping screw (the upper intermediate one) is off center, so that there is only one way that the units can be joined.

¹⁵ When the louver clamping screws 28 are manipulated to draw the louvers toward each other, the continuous flanges 15 of the L-shaped margins 13 are drawn against the surfaces C and D of the door A and the ²⁰ flanges 15 are adapted to lie snugly against said surfaces without marring them.

The bushings 26 are adapted to limit the tension which the flanges 15 can exert against the surfaces of the door or the like ²⁵ and when the ventilating closure is set up the open ends of the bushings are preferably situated close to (almost contiguous with) the plate or body 12 of the louver 11 (see Figs. 2 and 6). When the ventilator is to ³⁰ be inserted in a door having thickness greater or less than that of the door illustrated, bushings and screws 28 suitable to the thickness, longer or shorter than those shown, may be utilized.

³⁵ It is evident that the portion or margin 13 of either or both louvers 10, 11 could be of configuration different from that shown and could be a separate piece of material secured to the louver and against a door or ⁴⁰ the like in any manner, as, for example, by the screws 28, or either of the portions or margins 13 could be omitted. In this latter event, screws (not shown) passing through the portion 13 utilized and entering the door ⁴⁵ or the like could constitute the means for incorporating the ventilating closure in the opening of the door or the like, and all of the units of the ventilator could be assembled before they were furnished to the trade. ⁵⁰

Having thus fully described the invention, what I claim as new and desire to secure by Letters Patent is:

1. In combination with a structure having an opening and walls adjacent said opening, ⁵⁵ a ventilating closure comprising spaced apart louvers adapted to cover said opening, each louver including a plate having apertures and flanges adjacent said apertures and a double flange attached to said plate ⁶⁰ and constituting the margin of each louver,

each double flange comprising a continuous flange adapted to lie in said opening and a continuous flange adapted to be contiguous with a wall of said structure, an apertured slide associated with one of said louvers and ⁶⁵ arranged within its double flange to open or close the ventilating apertures of said louver, and means for drawing said louvers toward each other and against said walls.

2. A ventilating closure comprising ⁷⁰ spaced apart plates each having ventilating apertures and flanges adjacent said apertures, the apertures of the different plates being arranged in staggered relation and all of the flanges of the different plates extending toward the same edge of said closure to preclude direct vision therethrough, a double flange about the margin of each plate and adapted to extend beyond the wall of an opening to be filled, an apertured slide permanently associated with one of said plates, and means whereby said plates can be drawn toward each other to secure said closure in said opening.

3. A ventilating closure comprising ⁷⁵ spaced apart plates each having ventilating openings with oblique flanges, the openings and flanges of the different plates being arranged in staggered relation to preclude direct vision through the closure, a flange ⁸⁰ about the margin of each plate and extending therefrom in a direction opposite that in which the oblique flanges extend, said flange adapted to lie in an opening to be covered by said closure, a second flange about each ⁸⁵ of said last mentioned flanges, said second flanges being adapted to lie adjacent oppositely disposed walls of a structure having said opening, and means for drawing said marginal flanges of the different plates ⁹⁰ toward each other to clamp said second flanges against said walls.

4. A ventilating closure as specified in claim 3, wherein an apertured ventilating member is situated within one of said marginal flanges to open or close the ventilating apertures through said plates.

5. In a ventilating closure, a plate having a marginal flange, spaced apart strips secured to and spaced from said plate, and an ¹¹⁰ adjustable member situated between said strips and plate, each strip being spaced from said plate by annular flanges integral with said strip and being held to said plate by hollow rivets entering said annular ¹¹⁵ flanges and plate.

Signed at Bridgeport, in the county of Fairfield, and State of Connecticut, this 8th day of March A. D., 1923.

ANDREW L. RIKER.
